DESIGN FOR WALLPAPER

Frank Urschel, St. Louis, Mo.

Application July 1, 1944, Serial No. 114,283

Term of patent 3½ years

(Cl. D59—10)

To all whom it may concern:

Be it known that I, Frank Urschel, a citizen of the United States, residing at St. Louis, in the State of Missouri, have invented a new, original, and ornamental Design for Wallpaper, of which the following is a specification, reference being had to the accompanying drawing, forming part thereof.

The figure is a plan view of wallpaper, showing my new design.

I claim:

The ornamental design for wallpaper, as shown.

FRANK URSCHEL.
